UNITED STATES PATENT OFFICE.

PEMBROKE D. HARTON, OF PHILADELPHIA, PENNSYLVANIA.

CAKE-COATING MACHINE.

Specification of Letters Patent. Patented Feb. 22, 1916.

1,172,357.

Application filed February 21, 1914. Serial No. 820,168.

To all whom it may concern:

Be it known that I, PEMBROKE D. HARTON, a citizen of the United States, residing in Philadelphia, Pennsylvania, have invented 5 certain Improvements in Cake-Coating Machines, of which the following is a specification.

The object of my invention is to provide improved mechanism for applying coating 10 or icing materials to small cakes, and it is more particularly directed to means for simultaneously applying a plurality of materials.

The machine to which my present improvements have been applied may be substantially similar to that illustrated in my prior Patent, No. 1,036,108, Aug. 20, 1912.

My present improvements relate more particularly to the means for effecting delivery of the coating material from the receptacles containing the same, such delivery taking place at a common point where portions of the separate bodies of coating materials may be discharged axially with 25 respect to each other, from nozzles or orifices in a fixed head.

An important object of my invention is to provide means for positively separating a portion of the coating material from the 30 main body of the same, from which smaller body the portion subsequently ejected upon the cakes is taken. When the action of discharging or delivering the coating material is completed, the retraction of the means effecting the same produces a quick, sharp 35 separation of the coating material within the nozzles from that on the cakes.

These and other features of my invention are more fully described hereinafter, reference being had to the accompanying drawings, in which:

Figure 1, is a side elevation of sufficient of a cake coating machine to illustrate my present invention; Fig. 2, is a sectional elevation on the line 2—2, Fig. 3; Fig. 3, is an enlarged plan view of my improved mechanism for discharging the coating material; Figs. 4, 5, 6 and 7, are diagrammatic views of a part of the mechanism shown in Fig. 2, illustrating such mechanism in different positions; Fig. 8, is a section on the line 8—8, Fig. 2, and Figs. 9 and 10, are detailed perspective views illustrating details of my improved mechanism.

In the drawings, 1, 1, represent the side frames of the machine on which are mount-

ed a series of shafts suitably geared together, as hereinafter described; the main driving shaft 2 carrying a driving pulley 3. Mounted on said shaft, between the side 60 frames, is a pinion 4, which meshes with a gear wheel 5, mounted on a shaft 6, paralleling the shaft 2. The pinion 4 also meshes with a pinion 7 mounted on a shaft 8, also paralleling the shafts 2 and 6, which pinion 65 7 in turn meshes with a gear wheel 9 mounted on a shaft 10. The shaft 6 also carries a gear wheel 11 meshing with a gear wheel 12 on a shaft 13, and the gear wheel 12 meshes with a gear wheel 14 on a shaft 15; 70 such elements being constructed and arranged all as hereinafter set forth. To avoid confusion, the teeth of the several gear wheels have been omitted.

The cakes to be coated may be placed on a table 20, and they are moved along step by step by suitable conveying mechanism 20^a, being transferred from said table to an endless belt conveyer 21, by a pushing or centering bar 22 operated by suitable mechanism, properly timed with respect to the cake conveying means, as more fully described in my prior patent before referred to. The bar 22 serves to transfer the cakes from the table 20 to the conveyer belt 21, and so arranges the cakes that on the next intermittent movement of the conveyer belt the cakes will be brought to a position beneath the center of a box or receptacle 23, from which a coating of jelly or other material may be deposited upon the cakes. At 90 the end of the next or third movement of the conveyer belt 21, the cakes are brought to a central position beneath another receptacle or hopper 25, and from this hopper the cakes receive a double deposit, axially delivered, which may consist of separate bodies of chocolate and marshmallow, or any other material desired.

The hopper 25 comprises an upper removable section 26, and a lower section 27 fixed to the side frames of the machine. The lower section 27 consists of two end frames 30—30, suitably spaced apart by bottom and side members 31 and 32, and such lower 105 section has a partition 33 extending the full length thereof, dividing the same into separate compartments 28 and 29. The removable section 26 also has a partition 34 dividing it into separate compartments 35 and 110 36. When the section 26 of the hopper is placed in proper position, the partition 34

thereof rests upon the partition 33 of the section 27, and the compartments 35 and 36 register with the compartments 28 and 29, thereby forming single compartments, respectively.

The bottom plate 31 of the section 27 is provided with an opening into which the partition 33 extends and forms the dividing wall of a pair of slots 38 extending the full 10 length of said plate, in which slots are mounted a pair of butterfly valves 39. These valves may be suitably operated simultaneously, to permit or to cut off flow of material from the compartments 28 and 29 15 to the nozzle carrying member 40.

Slidably mounted in the lower part of the compartments 28 and 29, and resting on the bottom plate 31, is a pair of bars 41 which act as plungers, being moved back and forth 20 within chambers 28^a and 29^a formed between a pair of flat, blade-like, cut-off bars 42, (operating directly above the plunger bars 41), and the bottom plate 31; said bars 42 also acting as knives to cut through the coating material and together as partitions to 25 separate the material in the chambers 28^a and 29^a from the main body of material in the compartments 28 and 29.

The plunger bars 41 do not extend the full 30 length of the compartments 28 and 29; filler plates 43 being provided between the ends thereof and the end plates 30 of the hopper. The bars or blades 42 extend the full length 35 of the compartments 28 and 29, however; a guideway being provided for the same between the top of the filler plates 43 and the lower edge of extensions 44 of end plates 45 of the removable section 26.

As shown in Fig. 2, a deposit of coating 40 material has been placed upon the cake α , which has previously been raised by the conveyer belt, the valves 39 being open, the knife bars 42 are in contact with the partition 33 and the plunger bars 41 in their extreme inward position having forced the material through the slots 38, past the valves 39. In the next movement shown in Fig. 4, the plunger bars 41 have started to move outward (in the direction of the arrows) 45 causing suction in the chambers 28^a and 29^a, thereby drawing the material up through the slots 38, breaking the same from the cakes, which at this point of the operation are lowered by the conveyer belt 21, in a manner hereinafter described, simultaneously 50 with the commencement of the outward movement of the plunger bars 41. During this part of the outward movement of the plungers 41, the knife bars 42 and the butterfly valves 39 remain stationary.

Upon a continued movement of the plunger 55 41 in the direction of the arrows, (Fig. 5) the valves 39 are turned to the closed position and the knife bars 42 receive a quick 60 outward movement to the position shown in

Fig. 5. This causes the plungers 41, in their outward movement, to draw a new charge of material from the compartments 28 and 29 into the chambers 28^a and 29^a; the movement of the plungers continuing until the 70 position shown in Fig. 6 is reached. During this period, a row of coated cakes has been moved away from the nozzle member 40 and a fresh row of uncoated cakes has been brought under the said nozzle member 75 by the conveyer belt 21; the cakes being raised to a position ready for coating by suitable mechanism, hereinafter described, controlled by the shaft 13. The next operation is to impart a quick inward movement 80 to the knife bars 42, separating the material in the chambers 28^a and 29^a from the bulk of material in compartments 28 and 29. At the same time the valves 39 are opened (Fig. 85 7), and the plungers 41 continue to move in the direction of the arrows until the position shown in Fig. 2, is again reached, completing the deposit of material upon the line of cakes positioned under the nozzles in the member 40.

Movement is imparted to the plunger bars 41 by a pair of suitably shaped cams 50 and 50^a, one of which is mounted on the shaft 6; the other being mounted on the shaft 10. A pair of adjustable levers 51 and 51^a are 90 pivoted to the frame 1 of the machine at 52 and 52^a. The levers 51 and 51^a carry rollers 53 and 53^a which ride on the periphery of the cams 50 and 50^a, being held in contact therewith by means of weights 55 and 55^a 95 carried by the outer end of said levers. The levers 51 and 51^a are slotted at 56 and 56^a for the reception of internally threaded blocks 57 and 57^a; said blocks having lugs 58 and 58^a to which are pivoted links 59 and 100 59^a; the opposite ends of said links being connected to levers 60 and 60^a carried by the ends of rock shafts 61 and 61^a. Each rock shaft 61 and 61^a also carries a pair of levers 62 and 62^a; the lower ends of which 105 are connected to links 63 and 63^a, and the latter connected to rods 64 and 64^a slidably mounted in the side walls 32 of the section 27. The inner end of said rods 64 and 64^a are provided with heads 65 and 65^a 110 arranged to fit openings 66 in the bars 41; said bars having slots 67 to accommodate the reduced portions 68 and 68^a of the rods 64 and 64^a. The peculiar shape of the periphery of the cams 50 and 50^a, which are rotated by 115 the beforementioned gearing, causes the plungers 41 to be reciprocated. The amount of movement imparted to said plungers may be varied by operating the hand wheels 70 and 70^a carried by the levers 51 and 51^a, 120 thereby turning the screws 71 and 71^a and moving the nuts 57 and 57^a toward or away from the pivotal connections of said levers. The movement of the plungers 41 may be 125 decreased by moving the nut 57 or 57^a 130

toward the pivotal connections 52 or 52^a until said nuts are directly over the said connections, at which time the plungers 41 will receive no movement. To give the 5 plungers 41 their full movement, the nuts 57 and 57^a are moved to the extreme ends of the slots 56 and 56^a in the levers 51 and 51^a. Movement is imparted to the knife bars 10 42 and butterfly valves 39 through the medium of a pair of cams 80 and 81 on the shaft 15. A rod 82 connected at its upper end to a lever 83 mounted on a rock shaft 84, is provided with a head 85 at its lower end. This head 85 carries a pair of 15 rollers 86 and 87 in contact with the cams 80 and 81, respectively; said cams raising and lowering the rod 82 to give the knife bars 42 and valves 39 their desired movements at the proper time. The lever 83 20 has an extension 88 connected by a link 89 to a lever 90 carried by the outer end of one of the valves 39. The valves 39 are also provided with meshing pinions 91, so that movement imparted to one of said valves 25 will be communicated directly to the other. The rock shaft 84 also carries a lever 92 connected by a link 93 to a lever 95 mounted on another rock shaft 96. The rock shafts 84 and 96 each carry a pair of levers 97, 30 having slots 98 through which a rod 99 passes; said rod connecting a pair of slide rods 100 having heads 101 adapted to notches or slots 102 in the bars 42. When the shaft 15 is rotated, it gives the proper 35 movement to the knife bars 42 through the series of cams, links, shafts and levers just described. The rock shafts 61, 61^a, 84 and 96 may be mounted in bearings formed in an extension of the end plates 30 of the 40 lower section 27 of the hopper 25.

For the purpose of cleaning the hopper 25 and its internal operating parts, the upper section 26 is made removable, for which purpose the lower section 27 is provided with bolts 105 pivoted thereto at 106; the bolts 105 passing through slots 107 formed in the end of the upper section 26 and having thumb nuts 108. The nuts 108 may be backed off and the bolts 105 thrown 50 out of the slots 107 to permit removal of said upper section 26. The portion 44 being an integral part of the upper section 26, is also lifted from the top of the knife plates 42. The knife bars 42 can then be 55 removed by grasping the lugs 109; the heads 101 of the rods 100 sliding out of the slots 102 in said bars. The plunger bars 41 can then be removed in like manner, and the entire internal portion of the hopper 25 60 is ready for cleansing in any suitable manner. The partition 34 may be removed from the upper section 26, for the purpose of filling said section 26 with but one class of coating material; said partition being 65 held in grooves formed in the end plates 45.

In order to raise the cakes to a position to be coated, the shaft 13 is provided with a cam 110, operating against a roller 111, carried by a head 112 mounted on the lower end of a rod 113, the upper end of which is 70 adjustably pivoted to a lever 114. The said lever is mounted on one end of a shaft 115, journaled in the side frames of the machine, and carries a pair of levers 116, the outer ends of which operate on the under 75 side of a bar 117 extending the full width of the machine, over which the belt conveyor 21 moves to raise said bar 117. The bar 117 is adapted to slide vertically in grooves 118 formed in the side frames 1, 1, 80 of the machine. The shaft 115 carries at the end opposite the lever 114 a weight 119 for the purpose of automatically lowering the bar 117 when the roller 111 is in contact with the low side of the cam 110. 85

I claim:

1. In a cake coating machine, the combination of a frame, an icing receptacle carried thereby having a discharge head, said head having a plurality of nozzles with plural discharge orifices axially arranged, said receptacle having passages leading to the respective discharge outlets, a pair of laterally movable plungers extending substantially the full length mounted in the lower part 95 of said receptacle and serving to force the material through said passages to the nozzles, and a pair of horizontally disposed partitions laterally movable and forming chambers in the bottom portion of said receptacle in which said plungers may move. 100

2. In a cake coating machine, the combination of a frame, an icing receptacle carried thereby having a discharge head, said head having a plurality of nozzles with plural discharge orifices axially arranged, said receptacle having passages leading to the respective discharge outlets, bars extending substantially the full length of said head 110 and forming rocking valves in each of said 115 passages, a pair of laterally movable plungers extending substantially the full length and mounted in the lower part of said receptacle above the valves, said plungers serving to force the material past said valves when they are open and through said nozzles, a pair of horizontally-disposed partitions laterally movable above said plungers and forming chambers in the bottom portion of said receptacle in which said 120 plungers may move and means for operating said valves. 125

3. In a cake coating machine, the combination of a frame, an icing receptacle carried thereby having a discharge head, said head having a plurality of nozzles with plural discharge orifices axially arranged, said receptacle having passages leading to the respective discharge outlets, bars extending substantially the full length of said head 130

and forming rocking valves in said passages, a pair of laterally movable plungers mounted in the lower part of said receptacle and serving to force the material through said nozzles when said valves are open, means for opening and closing said valves, and means independently thereof for actuating said plungers.

4. In a cake coating machine, the combination of a frame, an icing receptacle carried thereby having a discharge head, disposed in fixed position with relation to the frame said head having a plurality of nozzles with plural discharge orifices axially arranged, said receptacle having passages leading to the separate discharge outlets of the respective nozzles, horizontally movable partitions arranged in the discharge head to separate portions of the coating material from the main body and forming chambers in the bottom portion of the separate compartments in said head communicating with the receptacle, and plungers below said partitions and serving to force the material in said chambers through the discharge orifices of the respective nozzles.

5. In a cake coating machine, the combination of a frame, an icing receptacle carried thereby having a discharge head disposed in fixed position with relation to the frame, said head having a plurality of nozzles with a pair of discharge orifices axially arranged, said receptacle having passages leading to the respective discharge outlets, pivotally mounted bars forming rocking valves in said passages, means for operating said valves, laterally movable plungers mounted in the lower part of said receptacle and serving to force the material through said nozzles, when the valves are open and means above said plungers for separating the material operated upon by said plungers from the main body of the material in the receptacle.

45 6. In a cake coating machine, the combination of a frame, an icing receptacle carried thereby having a discharge head disposed in fixed position with relation to the frame, said head having nozzles with a pair of discharge orifices axially arranged, means for moving rows of cakes beneath said orifices, said receptacle having passages leading to the respective discharge outlets, bars extending substantially the full length of said head and forming valves in said passages, laterally movable plungers mounted in the lower part of said receptacle and serving to force the material through said nozzles, means for reciprocating said plungers, movable partitions above said plungers and forming chambers in the bottom portion of said receptacle in which said plungers may move, and means for raising and lowering the cake moving means to bring rows of cakes into coating position

beneath the discharge nozzles and break the connection therewith respectively.

7. In a cake coating machine, the combination of a coating material receptacle having a discharge head disposed in fixed position with relation to the frame, said head having a plurality of nozzles, said receptacle having a passage leading to the discharge outlets, a bar extending substantially the full length of said head and forming a rocking valve in said passage, and superposed laterally movable members mounted in the lower part of said receptacle above the valve, the lower member serving to force the material through said nozzles, and the other member forming a chamber in the bottom portion of said receptacle in which the first-mentioned member may move.

8. In a cake coating machine, the combination of a coating material receptacle having a fixed discharge head, said head having a plurality of pairs of nozzles axially arranged, a partition within said receptacle dividing it into two compartments and extending to the discharge head, said receptacle having passages in its lower part leading from the respective compartments to separate sets of the axial discharge outlets, horizontally movable blades forming partitions arranged to separate portions of the coating material from the main body and forming chambers in the bottom portion of the separate compartments in said receptacle, plungers below said blades serving to force the material in said chambers through the discharge orifices, bars extending substantially the full length of said head and forming rotatable valves controlling the discharge of the coating material, and means independently of the blade and plunger actuating mechanism for operating said valves.

9. In a cake coating machine, the combination of a receptacle for coating material, a plurality of pairs of discharge nozzles carried by said receptacle for delivering such coating material, a plurality of sets of laterally sliding members movable in two directions, one set of said members effecting delivery of the coating material to said nozzles when moved in one direction and retracting such material from said nozzles whereby the connection between material within the nozzles and that upon the cakes may be broken when moved in the other direction and the other set forming in one position chambers for the movement of the members delivering the coating material, guideways for said members, rods detachably connected to said members, a plurality of rock shafts, arms carried by said rock shafts and operatively connected to said rods, means for operating said rock shafts whereby the movement of said several laterally movable members will be effected at different times, means for regulating the extent of movement of said sev-

eral laterally movable members, bars extending substantially the full length of said head and forming oscillating valves to control the passage of the coating material to the nozzles, and means independent of the operation of the laterally movable members but coördinating therewith for actuating said valves at the proper intervals.

10. In a cake coating machine, the combination of a receptacle for coating material, a plurality of pairs of discharge nozzles therefor carried by said receptacle, a pair of sliding members laterally movable in two directions, said members effecting delivery of the coating material to said nozzles when moved in one direction and retracting such material from said nozzles whereby the connection between material within the nozzles and that upon the cakes may be broken when moved in the other direction, guideways for said members, sliding plates above said members and forming when in one position chambers in which said members may move, rods detachably connected to said members

and the sliding plates, a plurality of rock shafts, arms carried by said several rock shafts and connected to said several rods, means for regulating the extent of movement of said laterally movable members and the sliding plates, means for operating said rock shafts whereby the movement of said laterally movable members and the sliding plates will be effected at different times, bars extending substantially the full length of said head and forming oscillating valves to control the passage of the coating material to the nozzles, and means independent of the operation of the laterally movable members and the sliding plates but coördinating therewith for actuating said valves at the proper intervals.

In testimony whereof, I have signed my name to this specification, in the presence of two subscribing witnesses.

PEMBROKE D. HARTON.

Correction in Letters Patent No. 1,172,357.

It is hereby certified that Letters Patent No. 1,172,357, granted February 22, 1916, upon the application of Pembroke D. Harton, of Philadelphia, Pennsylvania, for an improvement in "Cake-Coating Machines," were erroneously issued to the inventor, whereas said Letters Patent should have been issued to *Mary J. Harton as executrix of said Pembroke D. Harton, deceased*, as shown by the records of this office; and that the said Letters Patent should be read with this correction therein that the same may conform to the record of the case in the Patent Office.

Signed and sealed this 6th day of February, A. D., 1917.

[SEAL.]

R. F. WHITEHEAD,
Acting Commissioner of Patents.

Cl. 91—3.
